FOOT AND ARCH SUPPORT

Filed March 10, 1928

Inventor

A. Barbagallo

By *Watson E. Coleman*
Attorney

UNITED STATES PATENT OFFICE.

ALFREDO BARBAGALLO, OF WEST PALM BEACH, FLORIDA.

FOOT AND ARCH SUPPORT.

Application filed March 10, 1928. Serial No. 260,781.

This invention relates to a foot and arch support and it is an object of the invention to provide a device of this kind which can be readily applied within or removed from a shoe and wherein the support constitutes a separate part with respect to the shoe proper.

It is also an object of the invention to provide a device of this kind which operates when applied to the shoe to provide an effective support for the arch of a foot or to correct a tendency of the foot to lean toward or turn to one side.

Another object of the invention is to provide a device of this kind which is readily interchangeable with respect to different shoes at the will of the wearer, thus obviating the necessity of having a separate support for each shoe.

The invention consists in the details of construction and in the combination and arrangement of the several parts of my improved foot and arch support whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:-

Figure 1 is a view in side elevation of a foot and arch support constructed in accordance with an embodiment of my invention in applied position, the coacting shoe being indicated by broken lines;

Figure 2 is a sectional view taken substantially on the line 2—2 of Figure 1;

Figure 3 is a sectional view taken substantially on the line 3—3 of Figure 1;

Figure 4 is a view in bottom plan of the support as herein disclosed.

As disclosed in the accompanying drawing, S denotes a shoe of any preferred size and style and wherein 1 denotes the insole thereof. My improved support A in its entirety may be constructed of any desired material capable of the purposes intended and, as herein set forth, comprises a lamination 2 of sole leather shaved down along one marginal portion to provide a feather edge 3 after the lamination 2 has been cut to the desired shape to properly fit within the shoe S.

The lamination 2 gradually increases in thickness from the feather edge 3 to the opposite side edge of the lamination 2, said thickness being in accordance with the correction desired in the support of the foot. In the present embodiment of my invention this increased thickness is obtained by securing by adhesive or otherwise to the upper surface of the lamination 2 a layer or lamination 4 of felt, cork or other desired material. Disposed entirely over the upper surfaces of the lamination 2 and the layer or lamination 4 is a lining 5 of thin leather or other desired material preferably held in applied position by an adhesive. The side marginal portion of the lamination 2 remote from the feather edge 3 is defined by what might be termed an upstanding brace flange 6 which has close contact with a portion of the shoe vamp 7 immediately adjacent to the insole 1 and, as may be required, intermediate its ends the flange 6 is extended upwardly a material distance, as at 6', for coaction with that portion of the foot within the shoe which will so brace the foot to hold the same against leaning or turning toward one side. The length and height of the portion 6' in practice will be varied in accordance with the varying amounts of correction desired in the support of a foot.

It is also to be understood that in production my supports may be made for coaction with either side of a shoe and if found necessary the marginal flanges may be arranged along both sides.

To facilitate my improved device also serving as a support for high arches, an elongated spring metallic strip 8, preferably steel, may be inserted between the laminations 2 and 4 and extending preferably from the heel portion of the device to a point adjacent to the inner part of the sole portion.

It is to be noted that the flange 6 extends along the thickened marginal portion of the device from the toe end to the heel end and thus materially increasing the efficiency of the device in correcting a foot against turning or leaning movement.

From the foregoing description it is thought to be obvious that a foot and arch support constructed in accordance with my invention is particularly well adapted for use by reason of the convenience and facility with which it may be assembled and operated, and it will also be obvious that my invention is susceptible of some change and modification.

without departing from the principles and spirit thereof and for this reason I do not wish to be understood as limiting myself to the precise arrangement and formation of the several parts herein shown in carrying out my invention in practice except as hereinafter claimed.

I claim:—

10 A device for correcting a foot against leaning or turning movement comprising a member fitting within a shoe and resting upon the insole thereof and extending forwardly from

the heel end of the shoe, said member increasing in thickness from one side to the other, the thickened side marginal portion being extended as an upstanding flange, a lamination of yielding material secured to the member and disposed along the thickened side marginal portion thereof, and a reinforcing spring member interposed between the first 20 named member and said lamination.

In testimony whereof I hereunto affix my signature.

ALFREDO BARBAGALLO.
